Primary Examiner—Elizabeth A Albert*Assistant Examiner*—Karen E Eldridge Powers(74) *Attorney, Agent, or Firm*—Stoel Rives LLP(57) **CLAIM**

The ornamental design for a bodily fluid drainage bag cover, as shown and described.

DESCRIPTION

FIG. 1 is a front perspective view of an embodiment of a bodily fluid drainage bag cover in a partially raised state, showing my new design;

FIG. 2 is a front perspective view of the bodily fluid drainage bag cover of FIG. 1 in a lowered state;

FIG. 3 is a front elevation view thereof;

FIG. 4 is a right side elevation view thereof, with the left side elevation view being a mirror image of FIG. 4;

FIG. 5 is a top elevation view thereof; and,

FIG. 6 is a bottom elevation view thereof.

The broken lines immediately adjacent the shaded areas represent the bounds of the claimed design, while all other broken lines are directed to environment and are for illustrative purposes only; the broken lines form no part of the claimed design.
